GEORGE L. USSELMAN, OF ROCKY POINT, NEW YORK, ASSIGNOR TO RADIO CORPORATION OF AMERICA, A CORPORATION OF DELAWARE

CARRIER SUPPRESSION MODULATOR

Application filed October 5, 1928. Serial No. 310,457.

This invention relates to carrier suspension modulation, and more particularly to a method and means for increasing the efficiency of the usual type of carrier suppression modulator.

The typical carrier suppression modulator consists of a pair of three electrode vacuum tubes with an input circuit so arranged that carrier energy is supplied to the control electrodes of the tubes in parallel, while modulating energy is supplied thereto in series. The output circuit being connected between the anodes of the tubes, no carrier energy is developed therein, but the modulating energy and the side bands or beat frequencies of the modulation appear in the output circuit. Because the input circuit is capacitive for frequencies of the order of magnitude of the carrier and side band frequencies the feed back from the output circuit to the input circuit which takes place through the electrode capacitance of the tubes is degenerative in phase, and serves to diminish the desired beat frequency output. It is an object of my invention to overcome this source of power loss, for which purpose I apply sufficient regeneration of the heat frequencies to overcome the natural degeneration caused by the interelectrode coupling.

While the input circuit is capacitive for high frequencies it is inductive for frequencies of the order of magnitude of the modulating energy, and therefore the effect of the feed back to the input circuits is regenerative, which is undesirable because the modulating frequency is an undesired frequency in the output circuit anyway. Although this factor is reduced in importance by the tuning of the output circuit, it is not altogether negligible.

In accordance with my invention I apply sufficient degeneration of the energy of modulating frequency to overcome the natural regeneration thereof.

A certain amount of energy is transferred to the output circuit from the input circuit directly through the vacuum tubes as condensers, and not by reason of the usual vacuum tube action. This energy transferred is undesired, and is prevented by my invention.

All of the foregoing steps I accomplish in

a very simple manner by providing a pair of condensers each connected between the anodes of one of the tubes and the control electrodes of the other of the tubes, which, superficially, is similar to the neutralizing arrangements heretofore known, but the operation thereof is different because contrary to the usual function of neutralizing condensers, they provide regeneration for overcoming degeneration. At the same time the properties of the circuit are such that the desired and undesired frequencies are automatically discriminated between, so as not to provide regeneration of an undesired frequency, and actually to provide degeneration.

It is an object of my invention to still further increase the efficiency of a carrier suppression modulator, and this I do by overneutralizing the modulator, that is, by making the magnitude of the neutralizing condensers greater than what is necessary for correct neutralization, in which case the desired energy is given a certain amount of positive regeneration, while the undesired modulating energy is given a certain amount of positive degeneration.

The invention is described further in the following specification, which is accompanied by a drawing, the single figure of which is a wiring diagram for one form of my invention.

Referring to the drawing there is a pair of three electrode vacuum tubes 2, 4, to the control electrodes of which there is coupled an input circuit comprising an inductance 6 and the series condensers 8 and 10 connected in parallel therewith. The modulating energy is supplied from any suitable source 12 to a coil 14 which is coupled to the input coil 6. Carrier energy is supplied from a source 16, and is coupled between the condensers 8 and 10 and to the cathodes of the tubes, so that the carrier energy is fed to the control electrodes of the tubes in parallel.

The condensers 8 and 10 are blocking condensers which freely pass the carrier energy, and are not intended to resonate with the inductance 6. A pair of chokes 18 and 20 may be provided to isolate the modulating and carrier frequency paths.

The output circuit comprises an inductance 22, which, in the case of fairly constant frequency outputs, may be tuned by a tuning condenser 24. A speech side band may be 5 tuned if impressed on a high frequency carrier. The condenser is preferably two series condensers, simultaneously tuned by a single control. The choke 23 prevents the tuned circuit from splitting up into two tuned circuits, in its action. The output circuit is 10 connected between the anodes of the tubes 2, 4, as shown. The anodes are given a positive potential by a suitable direct current source connected to a lead 26, while the control electrodes are suitably biased by a source connected to the lead 28.

In accordance with my invention a pair of condensers 30 and 32 are connected, as shown, 20 each from the anode of one of the tubes to the control electrode of the other of the tubes, and are adjusted to compensate, or to more than compensate for the effect of the natural capacitance between the output and input circuits of the modulator.

25 The blocking condensers 8 and 10 are, of course, capacitive for high frequencies, and it is a known property of vacuum tube circuits that the feed back to a capacitive input circuit is degenerative, which serves to diminish the 30 magnitude of side band output. The condensers 30 and 32 serve to counteract this natural degeneration, and cause a desirable regeneration.

35 For low frequencies like the modulating frequency the input circuit is inductive, because the condensers 8 and 10 are a high 40 reactance to this low frequency, and therefore the latter takes the inductive path 6. The natural coupling is in this case regenerative, but inasmuch as the modulating frequency appearing in the output circuit is very undesirable, the regeneration is in this case also 45 undesired. The condensers may be used to provide a degeneration which reduces the magnitude of whatever modulating energy may appear in the output circuit.

50 Another effect of great value is that the added condensers serve to prevent a transfer of energy from the input circuit to the output circuit directly through the capacitance of the tubes, instead of through the tubes by their proper tube action. This desirable result is best obtained without over neutralization.

55 With respect to the carrier energy the arrangement produces a certain amount of degeneration, but this is not especially injurious inasmuch as more current can be fed from source 16. This will not require more power, as the added current is reactive current.

What I claim is:

1. In carrier suppression modulation, the method of augmenting the output of energy 35 of beat frequencies which includes providing

sufficient regeneration of the beat frequencies to overcome natural degeneration.

2. In carrier suppression modulation, the method of augmenting the output of energy of beat frequencies and diminishing the output of energy of input frequency which includes providing sufficient regeneration of the beat frequencies to overcome natural degeneration, and sufficient degeneration of an input frequency to overcome natural regeneration.

3. In carrier suppression modulation, the method of augmenting the output of energy of beat frequencies and diminishing the output of energy of input frequency which includes over-neutralizing the carrier suppression modulator, in order to provide positive regeneration of the beat frequencies, and positive degeneration of an input frequency.

4. The combination with a carrier suppression modulator comprising a pair of push-pull connected electron discharge devices having anodes, cathodes, and control electrodes, of capacitive means interconnecting the control electrodes and anodes to provide regeneration of the beat frequencies sufficient to overcome natural degeneration.

5. The combination with a carrier suppression modulator of reactive means to provide regeneration of the beat frequencies sufficient to overcome natural degeneration, and reactive means to provide degeneration of an input frequency sufficient to overcome natural regeneration.

6. The combination with a carrier suppression modulator employing electron emission tubes of reactive means to over-neutralize the effect of the natural tube capacitance in order to provide positive regeneration of the beat frequencies, and reactive means to provide positive degeneration of an input frequency.

7. The combination with a carrier suppression modulator comprising a pair of electron emission tubes, a source of modulating energy coupled to the control electrodes of the tubes in series, a source of carrier energy connected to the control electrodes of the tubes in parallel through reactances which are capacitive at the carrier frequency, and an output circuit coupled to the anodes of the tubes, of a pair of condensers each connected between the anode of one of the tubes and the control electrode of the other of the tubes for increasing the efficiency of the modulator.

8. An arrangement for carrier suppression modulation comprising a pair of electron emission tubes, and input circuit including an inductance and a pair of series connected condensers arranged in parallel with said inductance all connected in series with the control electrodes of the tubes, a source of modulating energy coupled to said inductance, a source of carrier energy coupled between the condensers and to the cathodes of

the tubes, an output circuit coupled to the anodes of the tubes, and a pair of condensers each connected between the anode of one of the tubes and the control electrode of the 5 other of the tubes for increasing the efficiency of the modulator.

9. In a carrier suppression system, a pair of discharge devices having input and output electrodes; a source of carrier energy and 10 a source of control energy coupled to the input electrodes of the devices, and means intercoupling the input and output electrodes of the devices to provide sufficient regeneration 15 of beat frequencies appearing in the output circuit of the devices, to overcome the natural degeneration of the devices.

10. In a carrier suppression system, a pair of discharge devices; a source of carrier energy coupled to the input electrodes of the 20 devices and a source of modulating energy coupled to the input electrodes of the devices in phase and in phase opposition respectively; and means intercoupling the input and output electrodes of the devices to provide 25 sufficient regeneration of beat frequencies appearing in the output circuit of the devices to overcome the natural degeneration of the devices.

11. In a carrier suppression system comprising a pair of coupled discharge devices having an input and an output circuit, the 30 method of overcoming natural degeneration of beat frequency energy appearing in the output circuit of the modulator which includes applying carrier and modulating energy to the input circuit of the devices in phase, and in phase opposition respectively; and regeneratively feeding beat frequency 35 energy from the output circuit of the devices to the input circuit thereof to overcome the 40 natural degeneration of the devices.
